UNITED STATES PATENT OFFICE.

HENRY M. FERGUSON, OF NEW ORLEANS, LOUISIANA.

PILE-DRIVER.

1,132,321.

Specification of Letters Patent. Patented Mar. 16, 1915.

Application filed December 13, 1913. Serial No. 806,560.

To all whom it may concern:

Be it known that I, HENRY M. FERGUSON, a citizen of the United States, residing at New Orleans, in the parish of Orleans and State of Louisiana, have invented new and useful Improvements in Pile-Drivers, of which the following is a specification.

The invention relates to an improvement in pile drivers, and more particularly to a base therefor mounted for adjustment to form an effective operation of the driver without regard to its position with respect to the horizontal center line of the sheet piling so long as the vertical center line of the driver and pile are in vertical alinement.

The main object of the present invention is the provision of a base for pile drivers in which the driving head is mounted for rotative movement within the base so that it may be turned to a proper position for effective coöperation with the sheet piling without regard as to whether the main body of the pile driver has the center horizontal line of the driving head and sheet piling in alinement thereby permitting, for example, the operation of the pile driver for driving sheet piling on both sides of the excavation without the necessity of shifting the pile driver as a whole.

The invention in the preferred form of details will be described in the following specification, reference being had particularly to the accompanying drawings, in which:—

Figure 1 is a perspective view illustrating the improvement. Fig. 2 is an elevation partly in section of the same, the driving head being shown at its lowest position. Fig. 3 is a similar view partly broken off with the driving head shown in its elevated position. Fig. 4 is a section on line 4—4 of Fig. 1. Fig. 5 is a section on line 5—5 of Fig. 1. Fig. 6 is a bottom plan of the head. Fig. 7 is a view similar to Fig. 3, showing the modified form of head.

In the accompanying drawings, the improvement is shown as applied to the ordinary type of steam pile driver hammer, wherein 1 represents the steam cylinder for actuating the plunger 2 through the medium of the piston rod 3, the plunger being mounted upon guide rods 4 depending from the frame 5 supporting the cylinder.

The improved base comprises a metallic section 6 centrally formed with an opening

7 extending entirely through the base, the upper portion of the opening being of a size to receive the driving projection 8 from the plunger 2, the lower portion of the opening 60 being circumferentially enlarged as at 9. At appropriate points, the base is formed with circular recesses 10 in which the lower ends of the guides 4 are fitted and secured by pins 11 passing through the base and 65 through the guides, the pins being readily removable to permit the disconnection of the base when desired. Slidably mounted in the enlarged portion 9 of the opening 7 is a driving disk 12, designed to directly receive the impact of the plunger.

The improved head comprises a driving section 13 from which rises a reduced cylindrical section 14 having a diameter corresponding to that of the portion 9 of the 75 opening 7, a further reduced section 15 rising from the section 14 and being provided on its upper end with a disk head 16 slidably fitting the portion 9 of the opening and having its upper surface of slight conical 80 formation to provide a central raised point 17 to receive the impact of the disk 12. By this means the impact of the disk is transmitted evenly and squarely to the head. The head is prevented from separation from 85 the base by means of lock bars 18 passing through the head and through the space of the opening 9 beyond the reduced body portion 15 of the head, whereby said lock bars will be engaged by the disk 16 and the head 90 thereby prevented from complete separation from the base. The driving section 13 of the head is formed in its bottom operative surface with a driving recess 19, the side walls of which throughout the central portion 95 thereof are upwardly and inwardly convergent, terminating in a narrow space 20 centrally of the bottom of the driving section to receive and center the head with respect to the sheet piling being driven. 100 Beyond the space 20, the walls are outwardly flared in bottom plan. This construction insures a proper coöperation of the driving section with the sheet piling and compels the maximum efficiency of the blow. 105

As will be apparent from the above description and drawings, the head as a whole is freely rotatable in the base and the driving section 13 is preferably provided with an annular series of openings 21 for the 110 insertion of the suitable instruments for turning the head in the base to adjust the

centering opening in the driving section with relation to the particular piling being driven.

The base 6 is preferably provided with 5 diametrically disposed channels 22 to receive channel irons 23 which may if desired seat in similar recesses in the plunger and extend the full length of the structure, the channel irons serving to fit between the pile 10 driver guides on the fixed frame. By means of the length of these channel guides, the device as a whole may be lowered for a considerable distance below the fixed frame, and hence increase its operative length at 15 will.

In Fig. 7 I have shown the identical construction except that in this instance the driving head terminates below the section 15 in a disk face 24. This type of head is 20 used in driving round piling.

The operation of the device will be fully apparent from the above description, it being obvious that the plunger transmits the impact to the head through the driving disk 25 12 and that the base follows up the driving movement until limited by contact of the locking rods with the upper edge of the section 14 of the head.

The improvement is particularly advantageous 30 in pile drivers for sheet piling, as it permits an adjustment of the head proper to effectively coöperate with the piling without regard to the position of the main por-

tion of the pile driver so long as said main portion is in approximately vertical alignment with the piling. 35

What is claimed is:—

1. A base for pile drivers including a section formed with a longitudinally extending opening to receive the driving element, 40 a head freely rotatable in said opening and having a portion of less diameter than the opening, locking pins passed through the base and seated in the opening adjacent the reduced space of the head, and a driving 45 disk freely movable in the opening and arranged above the head.

2. A base for pile drivers including a section formed with a longitudinally extending opening to receive the driving element, 50 a head freely rotatable in said opening and having a portion of less diameter than the opening, locking pins passed through the base and seated in the opening adjacent the reduced space of the head, and a driving 55 disk freely movable in the opening and arranged above the head, the upper end of the head being of conical formation to present a central impact point beneath the disk.

In testimony whereof I affix my signature 60 in presence of two witnesses.

HENRY M. FERGUSON.
